UNITED STATES PATENT OFFICE

FREDERICK A. ANTON, OF TOPEKA, KANSAS

LATERAL ARM AND ROLLER BRACKET SUPPORT

Application filed April 13, 1931. Serial No. 529,600.

This invention relates to lateral arm awning constructions and has for its object the production of a construction adapted for installation with modern store fronts particularly of the small specialty shops of various kinds.

In construction of this character it has heretofore been impossible to install a standard lateral arm awning on account of the fact that no transom bar is used and the partitions between adjacent stores are so small and narrow that there is no point for the support of such lateral arm awning constructions.

There has been a continuous demand for awnings of the construction of the character above-mentioned, but, so far as I am aware, no one has conceived of a construction whereby the strain of a lateral arm installation can be safely carried by such store fronts. The prime object, therefore, is to produce a unitary construction for installation on window display fronts, providing means carrying the operative parts of the awning so arranged that unevenness in the window front may be compensated for by adjustment of the operative parts of the awning structure, and a construction which does not materially interfere with light passing through the window.

With the general objects named in view and others as will hereinafter appear, the invention consists in certain novel and useful features of construction and combinations of parts as hereinafter described and claimed; and in order that it may be fully understood, reference is to be had to the accompanying drawing, in which:—

Figure 1 is a broken and fragmentary outer face view of a window front equipped with an assembly of lateral arm awning features, embodying the invention.

Figure 2 is an enlarged elevational view of part of the assembly.

Figure 3 is a vertical section on the line III—III of Figure 2.

Figure 4 is a vertical section on the line IV—IV of Figure 3.

Figure 5 is a section on the line V—V of Figure 3.

Referring to the drawing in detail, 1 indicates a store front window casing, and 2 the glass-supporting frame.

The awning assembly generally comprises a pair of brackets, a roller suitably journaled and supported by the brackets, means to revolve the roller to wind and unwind the awning fabric, not shown, hangers on the brackets and adjustable laterally so that they shall stand in true vertical planes regardless of whether the same is true of the window frame, lateral arms mounted on the hangers for swinging toward or away from the window and adjustable up and down for providing variations of pitch or inclination to the awning fabric when in spread or operative position.

The brackets 3 are of inverted right-angle triangle form, and flanged and beaded for lightness and strength, and of scroll form at their hypotenuse sides for attractiveness of appearance. Said brackets are fitted snugly in the upper corners of the window casing upon the top and side rails of the window frame and are detachably bolted thereto as at 4 so as to distribute the strain on the frame, imposed by the assembly and incidentally stiffen and strengthen said frame at the points where the strain is localized.

The awning roller 5 extends transversely of the window and is journaled at one end in a bearing bracket 5a. At the other end the roller fits nonrotatably in an angular socket of the shaft 6 journaled in a box composed of separable members 7 and 8 bolted together as at 9 and to the respective corner brackets 3, at 10. A gear wheel 11 is secured upon the shaft 6 within the box and engaged by a worm 12 on an operating shaft 13 depending from the box.

Pivottally suspended from bolts secured to the respective brackets 3, are hangers comprising flat bases 14, forwardly projecting necks 15 and transversely extending tubular heads 16. Plates 17 and 18 fit against opposite ends of said heads for rotatable adjustment therein, and through bolts 19 and retaining nuts 20 are employed to clamp said plates rigidly to the heads to guard against accidental rotary movement of the plates.

The hangers have forwardly projecting tubular noses 21 provided with circular sockets 22, and the hangers also have chambers 23 underlying the heads and arcuate slots 24 in the side walls of the chambers. Projecting into the chambers are screws 25 having spherical heads rotatable within said sockets 22 and held therein by protuberances 26 of the noses 21, and threaded on the screws 25 are collars 27 having oppositely-projecting pins 28 engaging perforated lugs 29 projecting into said slots 24 from the lower ends of plates 17 and 18. The plates 18 have laterally-projecting perforated lugs 30 providing journals for vertical bolts 31 to which the inner or rear ends of the lateral arms 32 are rigidly secured in any suitable manner.

From the foregoing it will be apparent that the operation of the screws 25 will effect rotation of plates 17 and 18 and thus effect the raising or lowering of the outer or front ends of the said arms 32, and that when the desired tilting adjustment of said arms is attained, the nut 20 is screwed more tightly 25 on bolt 19 to retain the arms at the pitch desired, it being understood that the pitch of the arms determines the slope or inclination of the awning fabric (not shown) when in spread or operative position.

30 In the event the window casing is slightly out of plumb, the hangers can be adjusted laterally to bring them to true vertical positions, by swinging adjustment on the upper or suspension bolts 33, the hangers having 35 arcuate slots 34 to accommodate these adjustments on the clamping bolts 35. To limit such adjustments the hangers have depending lugs 36 equipped with set screws 37 playing between a pair of lugs 38 projecting from the cross brackets whereby the hangers may be accurately adjusted so that the opposite ends of the awning shall operate in synchronism.

40 From the above description it will be evident that while I have described a construction embodying all of the features set forth as desirable, it is to be understood that I reserve the right to make all changes within the spirit of the invention and without the 45 ambit of the prior art.

I claim:—

1. A bracket for the support of window awnings formed along two of its sides with a reinforced braced securing edge adaptable 55 for detachable engagement with the upper corner of a window glass supporting frame and spaced from the glass carried by said frame, said bracket being of generally triangular form with means adjacent its right-60 angle corner to detachably support an end of an awning roller, the central area of said bracket being unobstructed for supporting an awning arm in adjustable relation to the bracket.
- 65 2. A bracket for the support of window

awnings formed along two of its sides with a reinforced braced securing edge adaptable for detachable engagement with the upper corner of a window glass supporting frame and spaced from the glass carried by said 70 frame, said bracket having means adjacent one corner to detachably support an end of an awning roller, the central area of the bracket being unobstructed for supporting an awning arm in adjustable relation to the 75 bracket.

In testimony whereof I affix my signature.
FREDERICK A. ANTON.
